CLAIM

The ornamental design for a sweater having an inside pocket with a doll in the pocket, as shown and described.

DESCRIPTION

FIG. 1 is a front plan view of a sweater with a pocket and doll which embody my design. The sweater is of conventional thickness;

FIG. 2 is an enlarged front plan view of the doll from FIG. 1;

FIG. 3 is an elevational view of said sweater from the bottom looking in the direction toward the top depicting said doll in said pocket;

FIG. 4 is a side elevational enlarged view of the doll from FIG. 3;

FIG. 5 is an elevational view from the top looking in the direction toward the bottom, with sweater arms folded;

FIG. 6 is the FIG. 5 elevational view with sweater arms fully extended;

FIG. 7 is a side elevational view of said sweater; and,

FIG. 8 is a back plan view of said sweater.
